Primary Examiner — Rhea Shields*(74) Attorney, Agent, or Firm* — Taylor IP, P.C.**CLAIM**

The ornamental design for the electrical receptacle with in-line power unit, as shown and described.

DESCRIPTION

FIG. 1 is a perspective view of an electrical receptacle with in-line power unit showing my new design; FIG. 2 is a side view thereof;

FIG. 3 is a front view thereof;

FIG. 4 is another side view thereof;

FIG. 5 is a back view thereof;

FIG. 6 is a top view thereof; and,

FIG. 7 is a bottom view thereof.

In the drawings, the broken lines depict unclaimed subject matter only and form no part of the claimed design.
